UNITED STATES PATENT OFFICE.

JOHN P. NECESSARY AND GUY E. SHINKLE, OF HUNTINGTON, WEST VIRGINIA.

DESIGN FOR A DISPLAY CABINET.

Application filed April 30, 1926. Serial No. 17,525. Term of patent 7 years.

To all whom it may concern:

Be it known that we, JOHN P. NECESSARY and GUY E. SHINKLE, citizens of the United States, residing at Huntington, in the county of Cabell and State of West Virginia, have invented a new, original, and ornamental Design for a Display Cabinet, of which the following is a specification, reference being had to the accompanying drawing, forming part thereof.

The figure is a perspective view of a display cabinet showing our new design.

We claim:

The ornamental design for a display cabinet, as shown.

JOHN P. NECESSARY.
GUY E. SHINKLE.
